UNITED STATES PATENT OFFICE.

FRED H. FOSTER, OF OXFORD, INDIANA.

FOLDING GASOLENE OR COAL-OIL STOVE.

1,182,548.

Specification of Letters Patent.

Patented May 9, 1916.

Application filed July 26, 1915. Serial No. 42,007.

To all whom it may concern:

Be it known that I, FRED H. FOSTER, a citizen of the United States, residing at Oxford, in the county of Benton and State of Indiana, have invented a new and useful Folding Gasolene or Coal-Oil Stove, of which the following is a specification.

The device forming the subject matter of this application is a folding stove of that general type which is adapted for use in connection with fluid fuel.

The invention aims to provide novel means whereby a stove of the type above mentioned may be maintained in a horizontal position, or be folded into a vertical position, the fuel delivery conduit remaining continuous and unbroken whether the stove be disposed horizontally or vertically.

Another object of the invention is to provide novel means whereby when the stove is in a folded or downwardly swung position, the bracing structure will be so disposed that a table or the like may be used in connection with the stove.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:—Figure 1 shows the invention in front elevation; Fig. 2 is a top plan; Fig. 3 is an end elevation showing the stove disposed horizontally; Fig. 4 is an end elevation showing the stove disposed vertically; Fig. 5 is a transverse section, the stove being disposed horizontally; Figs. 6, 7, 8, 9, 10 and 11, are diagrams representing the manner in which the bracing structure of the stove is folded.

In carrying out the present invention there is provided a fuel supplying conduit comprising a pipe 1, closed at one end by a cap 4, an extension 8, and a coupling 5 uniting the extension 8 with the pipe 1, so that the pipe and the extension may rotate

with respect to each other. The extension 8, if desired, may be flexible, and may be of any desired length, to the end that the fuel tank, not shown, may be disposed adjacent the stove, or at some distance therefrom. The pipe 1 which is rigid, is journaled for rotation in brackets 2 carried by a substantially vertical support 20 which may be the wall of a room. The pipe 1 preferably is removably mounted in the brackets 2, so that the pipe 1 and the stove which is carried thereby may be moved readily from place to place. The stove embodies a platform 16 carrying burners 17. T's 18 are interposed in the pipe 1, and pipes 19 connect the T's 18 with the burners 17. Depending brackets 21 are secured to the rear edge of the platform 16 and terminate in eyes 31 engaging the pipe 1.

Mounted to swing on the pipe 1 are hangers 6 carrying pivot elements 11 slidable in slots 100 formed in links 15, the slots having lateral extensions 101 which receive the pivot elements 11 when the stove is set up as shown in Fig. 3. The links 15 are provided with notches 28 adapted to receive projections 27 on the ends 40 of links 23, one end of each of the links 15 being pivoted to one of the links 23, as shown at 29, intermediate the ends of the said links 23. The ends 40 of the links 23 preferably are laterally resilient. The upper ends of the links 23 are pivoted as shown at 22 to the platform 16 of the stove near to the front edge thereof.

In practical operation, when the stove is set up as shown in Fig. 3, the hangers 6 are in depending positions and abut adjacent their lower ends against the support 20. The links 23 and 15 are in alinement, the notches 28 and the projections 27 constitute interengaging elements preventing the links from knuckling in one direction and the pivot elements 11 are received in the extensions or seats 101 of the slots 100. Thus, the platform 16 of the stove is rigidly and securely supported in a substantially horizontal position.

The platform 16 of the stove may be swung into a vertical position as clearly shown in Fig. 4 and, by a proper manipulation the parts 6, 15 and 23 will assume the compact form shown in Fig. 4. When the structure is folded, nothing projects horizontally beyond the platform 16 and space is economized accordingly.

In Figs. 6, 7, 8, 9, 10 and 11 are shown a series of diagrams illustrating the manner in which the links and the hangers are folded to assume the positions of Fig. 4. Other operations possibly may be carried out to effect the desired result but the figures under consideration will illustrate one process whereby the end in view may be accomplished.

Having thus described the invention, what is claimed is:—

1. In a device of the class described, a substantially vertical support; a vertically swinging stove; a vertically swinging hanger resting against the support when the hanger is in a depending position; means for pivotally connecting the stove and the hanger with the support; a pair of links, one end of one of which is pivoted to the other link intermediate the ends of said other link; interengaging elements on the first specified link and on the end of said other link for holding the links alined and against buckling in one direction; and means for pivotally connecting the outer ends of the links respectively to the hanger and the stove.

2. In a device of the class described, a substantially vertical support; a fuel conduit comprising a substantially horizontal section, an extension, and a coupling uniting the extension with the section for relative rotary movement; support engaging means in which the conduit is journaled; a stove secured to the section and embody-

ing a burner; a connection between the burner and the conduit section; a vertically swinging hanger resting against the support when the hanger is in a depending position, the hanger being mounted to swing on the conduit; a pair of links, one end of one of which is pivoted to the other link intermediate the ends of said other link; interengaging elements on the first specified link and on the end of said other link for holding the links alined and against knuckling in one direction; and means for pivotally connecting the outer ends of the links respectively to the hanger and the stove.

3. In a device of the class described, a stove; a depending hanger; means for supporting the stove and the hanger for swinging movement; an abutment coacting with the hanger; a pair of pivotally connected links one of which is provided with a longitudinal slot in one end; interengaging elements on the links coacting detachably to prevent the links from knuckling; an element carried by the hanger and movable in the slot when the links are folded; and means for pivotally connecting the other link to the stove.

In testimony that I claim the foregoing as my own, I have hereto affixed my signature in the presence of two witnesses.

FRED H. FOSTER.
